United States Patent Office

Des. 215,746
Patented Oct. 28, 1969

215,746

LOAD SUPPORTING STAND

Wayne E. Hunnicutt, Big Bend, and Peter G. Rossbach,
Waukesha, Wis., assignors to Applied Power Industries,
Inc., Milwaukee, Wis., a corporation of Wisconsin

Filed July 15, 1968, Ser. No. 12,775

Term of patent 14 years

Int. Cl. D12—05

U.S. Cl. D41—1

Fig. 1

Fig. 2

Fig. 3

Fig. 4

Fig. 5

FIG. 1 is an isometric view of a load supporting stand showing our new design;

FIG. 2 is a side elevational view thereof, both side views being essentially identical;

FIG. 3 is a top plan view thereof;

FIG. 4 is a front elevational view thereof; and

FIG. 5 is a back elevational view thereof.

We claim:

The ornamental design for a load supporting stand, as shown and described.
